UNITED STATES PATENT OFFICE.

JAMES W. R. McLAUGHLIN, OF CANONSBURG, PENNSYLVANIA.

SPACING DEVICE FOR PUNCHING-MACHINES.

1,169,415.

Specification of Letters Patent. Patented Jan. 25, 1916.

Application filed April 7, 1915. Serial No. 19,834.

To all whom it may concern:

Be it known that I, JAMES W. R. McLAUGHLIN, of Canonsburg, in the county of Washington and State of Pennsylvania, have invented a certain new and useful Improvement in Spacing Devices for Punching-Machines, of which the following is a full, clear, and exact description, reference being had to the accompanying drawings, forming part of this specification, in which—

Figure 1 is a side elevation of punching apparatus provided with my spacing device; Fig. 2 is a vertical sectional view of the locking bar, showing its location between the blocks of the locking arms; Fig. 3 is a detached side elevation showing the locking arm, locking dog, locking bar stop fingers and operating cams. Fig. 4 is a plan view, partially in section, of the same; and Fig. 5 is an end view, partially in section, of the punch and spacing device.

My invention relates to a spacing device adapted to be used in connection with apparatus for punching metal, such as beams and girders, and it has for its object simplicity of parts coupled with accuracy and efficiency.

In the drawings 2 represents the casing of the punch mechanism below which is the punch 3 and die holder 4. Extending horizontally from the die casing 2, and rigidly bolted thereto is an arm 5 which is vertically bifurcated at its outer end, in which bifurcation is pivoted the hanging stop arms 6 which are separated from each other by the block 7 and the locking block 8 and 9, which blocks are bolted to and between the arms. Passing between the arms 6, below the block 8 and above the block 9 is the horizontal locking bar 10 which is so arranged that a forward movement of the bar is prevented by the blocks 8 and 9 binding thereon, the arm 6 tending to be drawn forward by any force exerted forwardly on the bar 10, one end of which is secured to the carriage, and thereby the blocks 8 and 9, which are secured to the arm 6 outside of the vertical line passing through the pivotal point of the arms, bind the block 8 downwardly and the block 9 upwardly, on the bar 10, thus preventing a forward movement of the carriage.

Extending upwardly from the base of the apparatus, and on each side of the same are the fixed vertical standards 11 in which is journaled the cam shaft 12, and in front of the standards 11 are similar standards 13

having a transverse horizontal bar or shaft 14, on which the ends of the locking dog arms 15 are journaled, the free ends of which are provided with locking dogs 16, which are adapted to drop in rear of shoulders 17, formed on or bolted to the lower ends of the spacing arms 6, the purpose of the dogs being to prevent a rear movement of the arms.

On the rear faces of the spacing arms 6, are spacing fingers 18, which are secured to the arms by screws 19, passing through slots 20 in the fingers, to permit the fingers to move up and down on the inclined face of the spacing arm, and extending laterally from the fingers are arms 21 which rest on the lifting levers 22 which are pivoted to the locking dog arms 15. Keyed to the cam shaft 12 is the cam 23, on which the arms 22 and 15 rest, and a cam 24 which is arranged to come in contact with the spacing arms 6 and move them rearwardly after the cam 23 has lifted the arms 22 and 15 out of the shoulders or latch 17.

Keyed to the cam shaft 12 is a crank arm 25 to the outer end of which is pivoted the lower end of the vertical arm 26, the upper end of which is pivoted to the rear end of a horizontal arm 27, the forward end of which is pivoted on a fixed journal 28. This arm 27 rests on a cam 29, which is keyed to the shaft 30 which operates the punch, the lower face of the arm having a recess 31 to permit of a rapid fall of the arm when the nose of the cam enters the recess.

The forward end of the locking bar 10 is secured to a standard or standards 32 which extend upwardly from the carriage 33 which is so supported on the wheels 34 as to slide thereon. Resting on the carriage 33 is a wooden templet 35 having spacing pins 36. Extending laterally from the carriage is an arm 37 to which the beam or other structural metal to be punched is secured.

The operation is as follows: The spacing fingers being in their lowered position against the first of the pins 36, the carriage 33 being locked by the blocks 8 and 9 bearing on the bar 10, and the arms 6 being locked by the dogs 16, the punch 3 is operated by the shaft 30 to punch the metal on the die holder 4, and, as the punch is lifted, the cam 29 raises the arm 27 which, through the arms 26 and 25, rocks the cam shaft 105 which first raises the arms 22 and 15 by the cam 23, to lift the spacing fingers 18 and

the locking dogs 16, and then moves the arms 6 rearwardly by the cam 24, which moves the blocks 8 upwardly and the blocks 9 downwardly, releasing the locking bar 10 and permitting the carriage 33 to be pushed forward so that when the nose of the cam 29 enters the recess 31 the arm 27 will drop and the fingers 18 will come in front of the second spacing pin, at the same time the arms 6 under the force of gravity swing forward to their forward position, again locking the bar 10 between the blocks 8 and 9, and the dogs 16 fall in rear of the shoulder 17 to prevent the arms 6 from swinging back. This locks the carriage 33 for the next punching operation.

From the foregoing description the advantages of my invention may be appreciated by those skilled in the art.

Having thus described my invention, what I claim and desire to secure by Letters Patent is—

1. In spacing apparatus for punching machine, the combination of a carriage or carrying device adapted to carry a templet, a locking bar secured to the carriage, a swinging arm having locking devices adapted to engage with the locking bar to prevent the forward movement of the same, a device for imparting movement to the swinging arm to release the locking bar, stop fingers, and devices for operating the stop fingers.

2. In spacing apparatus for punching machine, the combination of a carriage or carrying device, a locking bar secured thereto, a swinging arm having an opening through which the locking bar passes and having locking blocks adapted to engage with the

locking bar, devices for imparting motion to the swinging arm, stop fingers, and devices for operating the stop fingers.

3. In spacing apparatus for punching machine, the combination of a carrying device or carriage, a locking bar secured thereto, a swinging arm adapted to lock the bar, devices for intermittently imparting motion to the swinging arm, a device for intermittently locking the rearward movement of the swinging arm, and a device for raising and lowering the stop fingers.

4. In spacing apparatus for punching machine, the combination of a carrying device or carriage, a locking bar secured thereto, a swinging arm having a locking block above and below the bar adapted to lock the same, a cam adapted to retract the swinging arm, a locking dog adapted to prevent the rearward movement of the swinging arm, a device adapted to operate the locking dog, stop fingers adapted to engage with a templet, and a cam for operating the stop fingers.

5. In spacing apparatus for punching machine, the combination of a carrying device, a locking bar, a swinging arm adapted to lock the bar, a dog for locking the swinging arm, movable stop fingers, a cam for releasing the locking dog, a cam for releasing the locking bar, and operating mechanism.

In testimony whereof I have hereunto set my hand.

JAMES W. R. McLAUGHLIN.
